UNITED STATES PATENT OFFICE.

ROBERT E. NELSON, OF KEYSTONE, SOUTH DAKOTA.

ORE-SEPARATOR.

1,272,301.

Specification of Letters Patent. Patented July 9, 1918.

Application filed August 30, 1917. Serial No. 189,008.

To all whom it may concern:

Be it known that I, ROBERT E. NELSON, a citizen of the United States, residing at Keystone, in the county of Pennington and 5 State of South Dakota, have invented new and useful Improvements in Ore-Separators, of which the following is a specification.

This invention relates to ore separators 10 or concentrators and the object is to provide in connection with a suitable chute or sluiceway having riffles and other gold separating devices therein, one or more pressure chambers each having a comparatively 15 wide opening at the top protected by a screen and a restricted opening at the bottom, these pressure chambers discharging into receptacles provided with separating material of a fibrous nature, and the upper 20 edges of the chambers and receptacles being provided with flanged portions producing eddy currents and assisting in the separation of the gold from the refuse material.

Other objects will appear from the following description considered in connection 25 with the accompanying drawings:—

In these drawings,

Figure 1 is a perspective view.

Fig. 2 is a longitudinal section.

30 Fig. 3 is a view showing the sluiceway formed in sections.

The separator includes a flume 10 of suitable size and capacity, the bottom 12 of which is provided with an opening communicating with the transversely extending member 18' constituting a chute or sluiceway through which the material passes during the process of separation, the lower end of the sluiceway where the tailings are 35 discharged being designated 16. The opening in the bottom of flume 12 is covered with a screen 17 and the initial separation takes place at this point. A gate 18 may be provided at the upper end of portion 14 40 of the sluiceway. The various members of the separator are mounted to provide an incline corresponding with the character of the material to be treated, the degree of inclination being greater than that usually 45 provided in the operation of similar apparatus.

The upper portion 14 of the sluiceway is provided with a series of riffles 20' for effecting partial separation and with a

covering of fibrous material such as cocoa 55 matting at a point adjacent to the riffles for effecting further separation.

Below that portion of the sluiceway designated 14 is an intermediate portion provided with one or more hydraulic pressure 60 chambers 20 and 21, these chambers having communication with openings in the bottom of the intermediate section 18 and being covered by a wire screen or the like shown at 23. A depressed portion 24 extends from 65 one wall of the upper pressure chamber and communicates with the bottom portion of member 18' at a point somewhat removed from said chamber 20 in order to provide a passageway within which fine sand and gold 70 may collect, such material passing through the screen and being on its way to said pressure chamber 20. The upper portion of chamber 20 is provided with an inwardly and downwardly extending flanged portion 75 25, this portion also extending transversely of the sluiceway and producing eddy currents for assisting in the control and separation of the material. A similar pressure chamber 21 is located below chamber 20 80 and no further description in connection with that chamber need be added. Each chamber 20 and 21 is provided with a restricted lower portion having an opening 26 85 therein through which the material passes to a pipe 27 or 28 extending downwardly and conducting the fine sand and gold to a receptacle 29 or 30 properly positioned within a sluiceway or plurality of sluiceways 34 90 extending transversely with reference to the main sluiceway and having a downward inclination.

Each receptacle is of a capacity suited to the capacity of the apparatus as a whole and the lower end of the pipe extending into 95 the receptacle terminates at a point above the bottom of said receptacle. A further collecting device is located in each receptacle and is shown at 36 and 37. Cocoa matting is also employed as a suitable material for the separating device or devices last-named and each piece of matting is held in position by means of a weight 38 or 39 both the separating device and the weight being removable for the purpose of cleaning the 100 separating material or matting and for washing out the gold collected thereby.

Each receptacle is provided at its upper

end with an inwardly and downwardly extending flange 39 which produces eddy currents and facilitates in very great degree the effective operation of the apparatus.

5 As already stated, the refuse material, or that portion thereof which is not discharged from the receptacle just named, passes over the lower end of the sluiceway designated 16 and previous to passing out of said lower 10 end the material travels over an additional separating device comprising a sheet of cocoa matting designated 40.

The material within the receptacles 20 and 21 is under a considerable degree of hydraulic pressure, due to the volume of water contained therein, and the pressure thus secured has an important bearing upon the operation of the device. The water is free from excessive agitation and the particles of 20 gold will be gradually carried downwardly into the fibrous material in the bottom of the receptacles receiving the discharge from the pipes. These particles of gold will be held by the matting or fibrous material, the water 25 flowing out of the top of the receptacles, but being retarded and eddy currents being formed in view of the peculiar construction of the upper portions of the receptacles. The dirt and sand rise to the top and are 30 washed away. The weight 38 for holding the matting in the receptacles comprises a ring member formed of cast iron or the like. A piece of cocoa matting 42 is located 35 above the screen 23, and matting is also provided in the sluiceways 34 as shown at 43.

In Fig. 3 I have shown how the sluiceway may be formed in sections to permit of easy transportation, and have shown a piece of matting 46 over the top of the sluiceway, 40 for directing floating gold downwardly into the pressure chamber 20.

The material passing downwardly through flume 10 is discharged through the screen therein, and through gate 18 into sluiceway 45 18' passing over riffles 20' and then over mat 42 and screen 23, being deflected downwardly, in the form shown in Fig. 3, by mat 46.

Portions of the material pass into the first 50 pressure chamber or catch basin 20 and are discharged into receptacle 29, and other portions pass to catch basin 21 and are discharged into receptacle 30. The deflecting devices 25 assist in this operation. The 55 lighter portion of the material passes over the lower fibrous mat 40 where any valuable material remaining will be collected so far as it is possible to effect that result, the tailings passing from the lower end of the sluiceway.

Some of the material passes into the re-

ceptacles, as above indicated, and is caught by the fibrous material in the bottom thereof, and other portions are caught by the flanged members 39', the material remaining being caught by mat 43.

What is claimed is:—

1. In a separator, the combination of a trough like conductor for the flow of the gold bearing material and water, and separatory devices along the length of the conductor, each comprising a catch basin having a constricted outlet at the bottom thereof, a separating receptacle communicating with said outlet, and a screen extending 70 across the top of both basins, a sheet of fibrous material spaced from that first named for directing a current through the screen into said basin last named, and means projecting from the edges of the catch basins 75 into the path of the current for deflecting 80 the material carried thereby.

2. In a device of the class described, a sluiceway, a catch basin connected therewith and having an outlet portion, a pipe 85 connected with the outlet portion, a receptacle into which the pipe discharges, and removable deflecting devices within the receptacles each comprising an annular member having a central opening and having inwardly and downwardly turned flanges adjacent to the openings, said flanges being concentric with reference to the discharge pipe and of greater diameter than the latter, and fibrous material located within the 90 bottom of the receptacle.

3. In a separator, a sluiceway having a depressed portion formed in the bottom thereof, a chamber having an upper portion communicating with said depressed portion 100 and having a narrow lower portion provided with an exit aperture, said chamber being formed with inclined walls extending transversely of the sluiceway and a flanged portion extending from one inclined wall at 105 the upper edge thereof toward the middle of the chamber and in a direction opposite to that in which the material to be separated is caused to travel and said depressed portion having a second chamber below that 110 first named and formed with inclined walls and a narrower lower portion, the edge of the depressed portion terminating in a flanged portion extending in the same direction as the flanged portion first named, but 115 being located at a higher level, and a screen connecting the flange of the depressed portion with the upper edge of said depressed portion.

In testimony whereof I affix my signature. 120

ROBERT E. NELSON.
